UNITED STATES PATENT OFFICE.

RALPH E. HEISEL, OF CHILlicothe, OHIO, ASSIGNOR TO THE MEAD PULP & PAPER COMPANY, OF DAYTON, OHIO, A CORPORATION OF OHIO.

PAPER-MAKING MACHINERY.

Application filed March 12, 1925. Serial No. 15,017.

This invention relates to paper making machinery, and more particularly to that portion of paper making machinery which has to do with the feeding of the paper making stock upon the forming part of the machine.

One of the principal objects of the invention is to provide a mechanism of this character which is constructed for easy adjustment to give suitable control of the flow of the stock from the flow box to the wire.

Another object of the invention is to provide mechanism of this character which is capable of local adjustment, in addition to adjustment as a whole, to compensate for operating irregularities, and to thereby give great nicety of control of the flow of stock.

Another object of the invention is to provide a device of this character which may be readily cleaned, and which permits of ready moving of the breast roll, as for the purpose of changing the wire, without the necessity of disassembling the device.

Other objects and advantages of the invention will be apparent from the description set out below when taken in connection with the accompanying drawing.

In the drawing in which like characters of reference designate like parts throughout the several views thereof—

Fig. 1 is a view in elevation of a device embodying the invention, the view being in a direction opposite to the direction of flow of the stock;

Fig. 2 is a side elevation of the device shown in Fig. 1;

Fig. 3 is a side elevation of the device with certain of the parts elevated into inoperative position to permit of removal of the breast roll; and

Fig. 4 is an enlarged detail view, in side elevation of the flow controlling mechanism, with parts broken away to more clearly illustrate the features of construction.

As showing a preferred embodiment the invention is illustrated in connection with a Fourdrinier type of paper making machine. In a machine of this type the pulp, or other fibrous material, suspended in water, is supplied to a flow box, whence it is fed through a suitable opening, at the desired rate, across a flow directing apron upon a traveling wire, which may or may not be given a transverse oscillatory motion, this wire being endless and suspended upon two rotatable rolls, the

roll at the flow box or inlet end being called the breast roll, and the roll at the other or outlet end of the wire being generally called the couch roll.

In the drawing the flow box is illustrated diagrammatically by the numeral 10, this flow box having suitable supporting frame work 11 associated therewith. Opening through the flow box adjacent the inlet side thereof is an outlet 12 through which the stock flows from the flow box and is uniformly distributed upon the wire. Associated with this opening is an apron 15 which is pivotally mounted upon the frame work 11 or some other fixed part of the mechanism, in association with the outlet 12, by means of suitable pivots 16 arranged at each end thereof. A stop member 17 is suitably mounted upon the frame work to limit the downward movement of the apron. This apron is extended a sufficient distance to overlie the breast roll 18, which is rotatably mounted and constructed in any suitable conventional manner. This breast roll carries a wire 20, and it will be noted that the apron overhangs the breast roll such a distance that its free edge lies substantially in a perpendicular plane passing through the axis of the breast roll. The apron is cut away at its forward or inlet edge, as shown at 21 to correspond to the curvature of the breast roll and the wire carried thereby.

In practice papers of many different grades will be made at different times upon a single machine. And a given kind of paper will be made in a number of different weights or thicknesses. Where it is desired to vary the thickness or weight of paper this is accomplished by properly controlling the quantity of stock which is flowed, per unit of time, upon the wire, this practice being too well recognized to need any discussion. In order to control the rate of flow of the stock upon the wire means is provided for varying the effective opening through which the stock flows from the flow box to the wire. This means is in the trade usually referred to as an "inlet", and wherever the word inlet is used herein it is meant to designate that mechanism associated with the flow box which controls the rate of flow of the stock from the flow box to the wire, and includes among other elements the apron, and a lip member designated generally by the numeral 30 which is adjustable with respect to the

- apron so that the effective opening between the lip member and the apron may be varied as desired.
- As shown the lip member 30 comprises an upper plate 31. This plate is provided along its rear edge with an enlargement 33 which is substantially circular in cross section this enlarged portion at each of its opposite ends being provided with an extension in the nature of a stub shaft 34 which is journalled in the frame 11. Mounted within the outlet opening of the flow box is a curved plate member 40 the front edge of which is recessed to receive the enlargement 33. This construction is such that the lip member may be swung up or down upon the supporting shaft portions 34, the recessed front edge of the member 40 serving to support the enlargement 33 throughout its length. Preferably the enlargement 33 and the recessed edge of the member 40 are constructed to give a sliding fit as the members rotate relative to each other. In order to assist in retaining the enlargement in place within the recessed edge of the plate 40 a retaining plate 41 is preferably bolted upon the upper face of the plate 40 this retaining plate being extended to overhang the enlargement 33 and thus retain it in position during operation.
- The plate member 31 is provided intermediate its width with a shoulder having a circular recess 45 which extends there-across. Mounted in this recess is a cylindrical enlargement 46, carried by the rear edge of the flexible plate 47, the front edge of which constitutes the effective front edge of the lip member. A retaining plate 48 is bolted to this shoulder, this plate having a recess 49 therein adapted to register with, and be complementary to, the recess 45, plate 31 and the retaining plate 48 thus functioning together to provide a recess receiving the enlargement 46. Adjacent its front edge, the flexible plate 47 has attached thereto, at suitable intervals, socket members 50 which are attached thereto in any suitable way. These members are shown in the drawing as being riveted to the plate 47 it being of course obvious that after attachment the ends of the rivets extending through the plate 47 would be dressed down to provide a smooth surface, as the existence of irregularities or projections upon the lower face of the flexible plate 47 would result in the accumulation of stock, or impurities, during operation of the device and such accumulation would in turn tend to make irregular the effective vertical opening through the inlet. If desired these socket members 50 may be brazed or soldered or attached in any other desired manner to the flexible plate. This flexible plate may be of any suitable flexible material, but brass constitutes a very satisfactory material, since it is sufficiently flexible, and may be readily deformed, and at the same

time is not subject to corrosion in the presence of water which is inevitably present in paper making machines. Each of the socket members has positioned therein, when the device is assembled, the head 52 of an adjusting bolt 53, which bolt is threadedly mounted within a bushing 54, this bushing being in turn threadedly mounted within a suitable passage in the upper plate 31. The adjusting bolt 53 and the bushing 54 are each provided with suitable hand wheels or the like, 55, for use in manipulation thereof. After the adjusting bolts are positioned to give desired warping or local adjustment of the flexible plate, the bushings 54 are manipulated to bring the lower end into frictional engagement with the upper face of the socket member to lock the device in the desired adjusted position.

During the paper making operation impurities tend to collect within the inlet, especially where hard water,—that is water having a considerable quantity of chemicals in solution therein,—are used. And such collected impurities will often materially vary the effective opening through the inlet. In order that the paper produced may be uniform throughout, it is necessary that substantially even distribution of the stock over the wire shall be secured. For if a greater quantity of stock is flowed to one portion of the wire than to another the paper will be thicker where this greater quantity of stock is flowed than it will be at the place where a lesser quantity of stock is flowed. Any material local variation in the effective opening through the inlet, therefore, will result in uneven distribution and non-uniformity in the paper. By means of the apparatus herein described this non-uniformity of flow may be prevented. For by properly manipulating the adjusting bolts 53 the edge of the flexible plate 47 may be locally adjusted or warped to give a vertical opening that will give a uniform rate of flow across the entire inlet. This warping of the flexible plate 47 is shown in Fig. 1, greatly in exaggeration, in order to more readily disclose this feature of the invention.

It is to be understood, of course, that in addition to this local adjustment or warping of the flexible plate 47 the entire lip member may be swung as a whole about the pivot shafts 34. The effective opening through the inlet for producing a given weight or grade of paper, is secured by swinging the lip member about its pivots. Then local adjustment, or fine adjustment or warping, of the flexible member 47 may be secured through suitable manipulation of the adjusting bolts 53.

It is to be noted that the joint between the enlargement 33 and the plate 40 is such that whatever may be the positioning of the lip member the lower surface of the

member 40 and the supporting plate 31, which surfaces are in contact with the flowing stock, will be unbroken and thus prevent no irregularities tending to cause the 5 accumulation of impurities or the like. And the same thing is true with respect to the joint between the flexible plate 47 and the supporting member 31.

For effecting adjustment of the lip member as a whole one of the pivot shafts 34, 10 extends entirely through the frame 11 and is provided at its outer end with a gear 60, preferably a worm gear of brass or the like. Cooperating with this worm gear 60 is a 15 worm pinion 61, mounted upon a suitable shaft 62, which is rotatably supported by the frame 11, this shaft having a hand wheel 63 upon the upper end thereof. By proper manipulation of the hand wheel rotary motion 20 may be imparted to the pivot shaft 34 to swing the lip member up or down as desired. In order to assist in operation of the machine, in the changing of the effective opening through the inlet, the gear 60 is 25 provided on its outer face with suitable indicating marks 65, a pointer 66 being attached adjacent the gear so that by means of suitable indicating characteristics any desired positioning of the lip member to secure a given rate of flow of the stock may be 30 had.

As is well known the length of life of the wires which are used in paper making machines is limited, and in usual practice these 35 wires must be changed about every ten days to two weeks. In changing the wire, which is endless, it is of course necessary to so move the breast roll and the couch roll relative to each other that after the old wire is 40 removed, a new wire may be readily slipped in place over these two rolls, after which the breast roll is replaced in its normal operating position. And in many paper making machines the breast roll is so mounted that 45 it must be lifted bodily upward in changing the wire. The apparatus forming the subject matter of this invention is particularly designed to facilitate this changing of the wire. In moving the breast roll to change 50 the wire it is not necessary to dismantle the inlet as is the case with other forms of inlets known, but the top member and the apron may be swung upwardly about their pivot mountings, out of the path of the 55 breast roll, so that that roll may be readily removed. This upward position of the apron and the top member is illustrated in Fig. 3. When in this elevated position cleaning of the apron and of the flexible plate 47 60 may be readily effected.

In order to facilitate this movement means is provided for interconnecting the lip member and the apron so that by proper manipulation of the hand wheel 63 the lip member 65 may be swung upwardly into inoperative

position, the apron member being concomitantly moved upon its mounting. This connecting means is preferably detachable so that it may be disconnected when the inlet is in operative position to permit of free adjustment of the lip member without varying the positioning of the apron member in any way. A very satisfactory form of attaching means is that shown in Fig. 3 of the drawing which consists of a chain 70, the 70 end links of which are connected to the plate 31 and the apron 15, respectively, by means of bolts or screws. If desired the end links of the chain may be formed so that they 75 may be readily slipped on or off the screws 80 71, or the device may be so arranged that the chain and the screws are entirely removed from the inlet, by unscrewing the screws.

As shown in Figs. 1 and 2 the undesirable 85 escape of the stock through the end of the inlet is prevented by means of a plate 75, which is bolted to the apron and snugly fits against the end of the lip member to prevent the escape of the stock between the 90 plate and the lip member. In addition there is a conventional showing of a deckle strap 76 which is mounted upon a deckle pulley 77, this pulley being shown as supported, 95 in a conventional manner, by brackets 78 mounted upon the flow box or its supporting framework.

While the form of apparatus herein described constitutes a preferred embodiment 100 of the invention, it is to be understood that the invention is not limited to this precise form of apparatus, and that changes may be made therein without departing from the scope of the invention which is defined in the appended claims.

What is claimed is:

1. In paper making apparatus of the character described comprising a flow box having an outlet opening therein, a wire supporting breast roll positioned adjacent thereto; a flow-controlling inlet pivotally mounted adjacent said outlet opening and overlying the breast roll and adapted to direct the flow of stock from the flow box through the outlet opening onto the wire, and means for swinging said inlet upon its pivotal mounting from its normal position overlying the breast roll, to permit removal of the breast roll.

2. In apparatus of the character described, the combination with a flow box, and the wire supporting breast roll positioned adjacent thereto of a flow-controlling inlet comprising an apron and a lip member each movably mounted in association with said flow box, and means for swinging the said apron and the said lip member upon their respective mountings at the same time.

3. In apparatus of the character described the combination with a flow box and a wire

- supporting breast roll positioned adjacent thereto, of a flow-controlling inlet associated with said flow box and overlying said breast roll, said inlet comprising a pivotally mounted apron, a pivotally mounted lip member associated therewith, and means for swinging the said apron and the said lip member about their pivots at the same time.
4. In paper making apparatus of the character described comprising a flow box, and a wire supporting breast roll positioned adjacent thereto; a movably mounted flow-directing apron associated with said flow box and overlying the breast roll, a movably mounted lip member cooperating with said apron and associated with the flow box, and means for moving the apron and lip member together out of their normal operating position overlying the said breast roll.
10. 5. In apparatus of the character described the combination with a flow box, and a wire supporting breast roll positioned adjacent thereto, of a movably mounted flow-directing apron associated with said flow box and overlying the breast roll, a movably mounted lip member associated with said flow box and cooperating with the said apron, means for moving the lip member upon its mounting and means connecting the lip member and the apron for causing concomitant movement of the lip member and the apron, the construction being such that the lip member and the apron may be moved at the same time out of their normal position overlying the breast roll.
20. 6. In apparatus of the character described the combination with a flow box, and a wire supporting breast roll positioned adjacent thereto, of a pivotally mounted flow-directing apron associated with the said flow box, a pivotally mounted lip member cooperating with said apron and associated with the said flow box, and means for concomitantly swinging the said apron and lip member upon their respective pivotal mountings, said means comprising a detachable link connecting the said lip member and the apron.
30. 7. In apparatus of the character described the combination with a flow box, and a wire supporting breast roll positioned adjacent thereto, of a pivotally mounted flow-directing apron associated with said flow box and overlying the breast roll, and a pivotally mounted lip member cooperating with said apron and associated with the flow box, means for swinging one of the said pivotally mounted members upon its pivotal mountings, and detachable means for connecting the two said pivotally mounted members, the construction being such that the apron and lip member are concomitantly moved from their normal position overlying the breast roll.
40. 8. In apparatus of the character described the combination with a flow box, and a wire supporting breast roll positioned adjacent thereto, of a pivotally mounted flow-directing apron associated with said flow box and overlying the said breast roll, and a pivotally mounted lip member cooperating with the said apron and associated with the flow box, and means for concomitantly swinging the said apron and lip member upon their respective pivotal mountings from their normal positions overlying the breast roll.
50. 9. In apparatus of the character described the combination with a flow box, and a wire supporting breast roll positioned adjacent thereto, of a movably mounted flow-directing apron associated with the said flow box and overlying the breast roll, a lip member, pivot shafts carried by said lip member and pivotally supported in cooperation with the said apron and in association with the flow box, link means connecting the said apron and lip member, and operating means associated with one of the said pivot shafts for causing movement of the lip member about said shaft.
60. 10. In apparatus of the character described, the combination with a flow box, and a wire supporting breast roll positioned adjacent thereto, of a movably mounted flow-directing apron associated with the said flow box and overlying the breast roll, a lip member, pivot shafts carried by said lip member and pivotally supported in cooperation with the said apron and in association with the flow box, flexible means connecting the said apron and lip member, and operating means associated with one of the said pivot shafts for causing movement of the lip member about said shaft.
70. 11. In apparatus of the character described, the combination with a flow box, and a wire supporting breast roll positioned adjacent thereto, of a movably mounted flow-directing apron associated with the said flow box and overlying the breast roll, a lip member, pivot shafts carried by said lip member and pivotally supported in cooperation with the said apron and in association with the flow box, detachable means connecting the said apron and lip member, and operating means associated with one of the said pivot shafts for causing movement of the lip member about said shaft.
80. 12. In apparatus of the character described, the combination with a flow box, and a wire supporting breast roll positioned adjacent thereto, of a movably mounted flow-directing apron associated with the said flow box and overlying the breast roll, a lip member, pivot shafts carried by said lip member and pivotally supported in cooperation with the said apron and in association with the flow box, link means connecting the said apron and lip member, and operating means associated with one of the said

- pivot shafts for causing movement of the lip member about said shaft, said means comprising a gear carried by the said pivot shaft, a pinion cooperating therewith, and operating means for said pinion.
13. In apparatus of the character described the combination with a flow box, and a wire supporting breast roll positioned adjacent thereto, of a flow-directing apron mounted in association with said flow box and overlying the breast roll, a lip member cooperating with the said apron and associated with the flow box, means for adjusting the lip member relative to the apron, and means carried by the lip member for adjusting the edge of the lip member relative to the apron without effecting bodily movement of the lip member.
14. In paper making apparatus of the character described comprising a paper forming part and a source of supply of paper forming stock; a flow-directing apron mounted in association with said source of supply, a lip member cooperating with the said apron to control the effective opening through which the paper forming stock is fed from the source of supply to the paper forming part, means for adjusting the lip member relative to the apron, and means independent of said first-mentioned means for effecting local adjustment of the edge of the lip member relative to the apron without effecting bodily movement of the lip member.
15. In apparatus of the character described, a flow-directing apron, a lip member cooperating with said apron comprising an adjustable upper plate and a lower flexible plate, adjusting bolts mounted in the upper plate and adjusting connections between the said bolts and the said flexible plate whereby warping of the flexible plate may be accomplished.
16. In apparatus of the character described a flow-directing apron, a lip member cooperating with said apron comprising an upper plate, a lower flexible plate, adjusting bolts mounted in the upper plate and flexibly connected to the lower plate whereby warping of the flexible plate may be accomplished, and means for holding each said bolt in any desired adjusted position.
17. In apparatus of the character described a flow-directing apron, a pivotally mounted lip member cooperating with said apron, means for swinging said lip member to vary the relative position of the lip member and the apron, said means comprising a gear rigidly connected with said lip member, a second gear cooperating with said first gear, and means for actuating said second gear.
18. In apparatus of the character described a flow-directing apron, a lip member cooperating with the said apron, a pivot shaft carried by said lip member, a gear on said shaft, a pinion for rotating the gear, means for operating the pinion, indicating marks on the gear and a fixed pointer associated therewith.
19. In apparatus of the character described, the combination with a flow box, and a wire supporting breast roll positioned adjacent thereto, of a lip member associated with said flow box and overlying said breast roll, said lip member including a flexible plate for controlling the flow of stock from said flow box onto said wire, means for locally adjusting said flexible plate across the width thereof, and means for moving said lip member from its position overlying said breast roll to a non-operating position, without disturbing said local adjusting means.
20. In apparatus of the character described, the combination with a flow box, and a wire supporting breast roll positioned adjacent thereto, of a flow-controlling inlet associated with said flow box and normally overlying the said breast roll comprising an apron and a flexible lip member, means for locally adjusting said flexible lip member across the width thereof relative to said apron, and means for moving said inlet from its position overlying said breast roll, said last-named means being independent of said local adjusting means.
21. In apparatus of the character described, a lip member comprising a movable upper plate, a lower flexible plate mounted on said upper plate, and means associated with said upper plate for locally adjusting said lower flexible plate.
22. In apparatus of the character described, a flow box having an outlet, and a lip member associated with said outlet, said lip member comprising a pivotally mounted upper plate, a lower flexible plate mounted on said upper plate, and means associated with said upper plate for locally adjusting said lower flexible plate, said parts being constructed and arranged to form a smooth unbroken flow-controlling surface for the stock issuing from said outlet of the flow box.

In testimony whereof I hereto affix my signature.

RALPH E. HEISEL.
